UNITED STATES PATENT OFFICE.

RICHARD FAIR, OF MOOSUP, AND SAMUEL P. DAVIS, OF DANIELSON, CONNECTICUT.

LOCOMOTIVE TURN-TABLE.

SPECIFICATION forming part of Letters Patent No. 752,539, dated February 16, 1904.

Application filed November 5, 1903. Serial No. 179,972. (No model.)

To all whom it may concern:

Be it known that we, RICHARD FAIR, residing at Moosup, and SAMUEL P. DAVIS, residing at Danielson, in the county of Windham and State of Connecticut, citizens of the United States, have invented certain new and useful Improvements in Locomotive Turn-Tables; and we do declare the following to be a full, clear, and exact description of the invention, such as will enable others skilled in the art to which it appertains to make and use the same.

Our invention is an improved turn-table for locomotives and cars using steam-power; and it consists in the construction and combination of devices hereinafter described and claimed.

The object of our invention is to provide an apparatus adapted for operation by the steam-power of a locomotive for turning a turn-table, so that the turn-table may be operated directly from a locomotive thereon and without the employment of other power than that which the locomotive furnishes.

In the accompanying drawings, Figure 1 is a perspective view of a turn-table embodying our improvements, the pit in which the turn-table is located being shown in section. Fig. 2 is a sectional view of the same, taken on the plane disclosing the driving-shaft.

The turn-table 1 here shown may be of any suitable construction and is located over a pit 2, the walls of which are shown at 3. The support 4 may also be of any suitable construction, but should be provided with a circular runway 5. The pivot of the turn-table is shown at 6, and the usual frusto-conical rollers 7 therefor bear and operate on the circular runway 5.

In the embodiment of our invention we provide the runway 5 with peripheral gear-teeth 38, which may be of sections bolted or otherwise secured to the periphery of the runway. We also provide a vertically-disposed driving-shaft 8, which has a bearing, as at 9, in the turn-table at a suitable distance from one side thereof, and also has a bearing, as at 10, in the brace 11, which is here shown as attached to the supporting-framework un-

der the turn-table. The track-rails on the turn-table are indicated at 12.

At one side of the track is a supporting-frame 13, which is upright, as shown, and which has a bearing 14 for the upper end of the driving-shaft 8. The said frame is also provided with bearings 15 for a vertical counter-shaft 16 and with bearings 17 for a vertical shaft 18. The shaft 16 has a spur-gear 19 near its upper end and a similar but somewhat larger gear 20 near its lower end.

On the shaft 18 is a loose spur-gear 21, which is vertically movable thereon, so that it may be disposed in position to engage or disengage the gear 19, and may be locked in either of said positions by a pin 22 inserted in an opening with which the shaft 18 is provided.

The shaft 8 is provided at its lower end with a pinion 23, which engages the gear 8, which is relatively fixed. Said shaft is also provided at a suitable distance above the turn-table with a friction-cone 24. A cylindrical sleeve 25 is loose on the shaft 8 above the friction-cone 24, and on the lower portion of said sleeve 25 is a sleeve 26, which is vertically movable thereon, is splined thereto, as at 27, is provided with a groove 28, formed between annular circumferential collars 29, and at the lower end of the said sleeve is a conical or frusto-conical friction-cup 30, which when the sleeve 26 is lowered serves to frictionally engage the friction-cone 24 to lock the sleeve 25 to the shaft 8, so that the latter will rotate with the former.

At the upper end of the sleeve 25 is a peripherally-spurred gear 31, which meshes with the spur-gear 20 of the shaft 16 and is provided on its upper side with an annular series of ratchet-teeth 32. A spur-gear 33, which is adapted to be engaged by the gear 21 when the latter also engages the gear 19, is loose on the shaft 8 and is provided with a depending sleeve 34. Said sleeve 34 carries a plurality of pivoted dogs 35, each of which is provided with a weighted arm 36. Said weighted arms serve to normally keep the pivoted dogs in engagement with the ratchet-gear 32 on the gear 31, and when the said dogs are turned to

a position to disengage the ratchet-gear the said weighted arms also serve to maintain the said dogs in the said disengaged position. Hence the gear 31, and consequently the 5 sleeves 25 26, may be locked to or released from the gear 33 at will. Normally the dogs 35 are engaged with the ratchet-gear 32, as shown in Fig. 1, and the gear 21 is out of engagement with the gears 19 and 33.

10 On rare occasions, when it becomes necessary or desirable to reverse the movement of the turn-table, the gear 21 will be shifted manually into engagement with the gears 19 and 33, as shown in Fig. 2.

15 At the upper end of the driving-shaft 8 is a motor 37, which in practice may be of any preferred type adapted for operation by steam from the locomotive and adapted to utilize the steam-power of the locomotive to rotate 20 the gear 33, and hence cause the shaft 8 to revolve in one direction, so that the gears 23 38 will cause the turn-table to rotate, the gear 23 moving orbitally around the gear 38, as will be understood.

25 In the embodiment of our invention here shown the motor 37 is of the rotary turbine type, in which the casing is secured to the frame 13 and is provided with a packing 39 for the shaft 8, and an impact-wheel or revolu- 30 ble element is loose on the said shaft and is fast to the gear 33, so as to rotate the latter. A flexible steam-pipe 40 supplies steam to the motor 37 from the boiler of a locomotive to be turned by the turn-table, the said pipe 35 40 being adapted to be coupled to a steam-connection of the boiler. The steam-exhaust pipe of the motor 37 is indicated at 41.

On the turn-table is a standard 42, to which is fulcrumed a shipping-lever 43, one arm of 40 which is bifurcated to form a yoke 44, that engages the annular groove 28 of the friction-clutch element 26, so that the shipping-lever is adapted for moving said friction-clutch element to lock and release the shaft 8. A spring 45 is employed to act on the said shipping-lever in such manner as to normally cause it to frictionally lock the friction-cup 30 to the friction-cone 24. Said spring is here shown as a coiled extensible spring having its lower end 45 connected to the shipping-lever and its upper end adjustably connected to the frame 13, so that its tension may be varied. The shipping-lever has an arm 46 and is also provided with a hand-lever arm 47. The arm 46 is provided 55 with a tappet-head 48 of suitable construction.

At one side of the turn-table the wall 3 of the pit is provided with a lock-opening 49. The turn-table is provided with a hinged gravity locking device 50, adapted to drop into the 60 opening 49 to automatically lock the turn-table when the latter reaches the required position.

Pivots mounted beyond the side of the turn-table opposite the lock-opening 49 is an 65 operating-cam 51, which may be moved into

and out of the path of the tappet-head 48 of the shipping-lever, the latter turning with the turn-table. Within the scope of our invention this operating-cam may be of any suitable construction and the same may be mounted in any suitable manner. It is here shown as adapted to lie in the path of the tappet-head 48 when turned inwardly and to depress said tappet-head as the latter passes under it, so as to turn the shipping-lever against the 75 tension of the spring 45 when the lock 50 drops into the lock-opening 49, so as to release the friction-clutch element 26 from the friction-cone 24, and hence cut off the application of power to the driving-shaft 8 when the turn-table is locked in the required position. To secure the operating-cam in position to thus engage the tappet-head of the shipping-lever, we provide a pin 52, which may be placed in or removed from the opening 53 in the plate or other suitable device 54. To permit the reengagement of the movable element of the friction-clutch with the driving-shaft to enable the turn-table to be again started when the lock device 50 has been 90 released from the opening 49, it is necessary to withdraw the pin 52, thereby releasing the cam 51, and then turn the latter outwardly to clear the tappet-head 48 of the shipping-lever. The clutch will then be automatically 95 locked by the action of the spring 45, as will be understood. By the provision of the lever-arm 47 the shipping-lever may be manually operated, if desired, or in the event that the automatically-operating cam 51 or tappet-head 48 should become broken or get damaged to such an extent as to be inoperative.

To lock the shipping-lever in the position assumed thereby when the clutch elements are disconnected from each other, we provide a 105 detent 55, which is pivotally mounted on an arm 56 with which the frame 13 is provided and operates by gravity to engage its jaw 57 with a stop 58, with which the shipping-lever is provided.

To turn the turn-table in the reverse direction, the dogs 35 must be disengaged from the ratchet-gear 32 and the gear 21 engaged with the gears 19 and 33, as shown in Fig. 2.

From the foregoing description, taken in 115 connection with the accompanying drawings, the construction and operation of the invention will be readily understood without requiring a more extended explanation.

Various changes in the form, proportion, 120 and the minor details of construction may be resorted to without departing from the principle or sacrificing any of the advantages of this invention.

Having thus fully described our invention, 125 what we claim as new, and desire to secure by Letters Patent, is—

1. In combination with a turn-table, a fixed gear, a power-shaft carried by and revolute- 130 slidably with the turn-table and having a pin-

ion engaging the fixed gear, a motor also carried by the turn-table, means, including a clutch device, connecting the motor to the power-shaft, and means to automatically operate the clutch device, to disconnect the motor from the power-shaft when the turn-table reaches the required position.

2. In combination with a turn-table, a motor and gear, including a clutch device, to rotate the turn-table, means to automatically lock the turn-table in the required position and means to automatically operate the clutch device to put the motor out of gear with the turn-table-rotating gear when the turn-table reaches such position, substantially as described.

3. In combination with a turn-table, a fixed gear, a power-shaft carried by and revoluble orbitally with the turn-table, and having a pinion engaging the fixed gear and motor, and means, including a clutch device, to drive the said shaft by the power of said motor.

4. In combination with a turn-table, a fixed gear, a power-shaft carried by and revoluble orbitally with the turn-table and having a pinion engaging the fixed gear and motor, and means to automatically operate said clutch device to disconnect the turn-table from the motor when the turn-table reaches the required position.

5. A turn-table having a motor, means operated thereby to rotate the turn-table, means to put said turn-table-rotating means in and out of gear, and a cam to automatically operate the said means for putting the turn-table-rotating means in and out of gear. 35

6. A turn-table having a power-shaft, means operated thereby to rotate the turn-table, a motor, a clutch to control the application of the power of the motor to said shaft, a shipping element, to operate said clutch, and means to automatically operate said shipping element when the turn-table reaches the required position. 40

7. A turn-table having a motor, a driving-shaft, means operated by the driving-shaft to rotate the turn-table, means to connect the motor to the driving-shaft to rotate the latter in either direction, means to disconnect the motor from the driving-shaft, and automatically-operating means to actuate said disconnecting means. 45 50

In testimony whereof we have hereunto set our hands in presence of two subscribing witnesses.
